UNITED STATES PATENT OFFICE.

WALLACE I. STIMPSON, OF HOPEDALE, MASSACHUSETTS, ASSIGNOR TO DRAPER CORPORATION, OF HOPEDALE, MASSACHUSETTS, A CORPORATION OF MAINE.

AUTOMATICALLY-THREADING SHUTTLE FOR LOOMS.

Application filed November 20, 1926. Serial No. 149,577.

This invention relates to automatically threading shuttles for looms wherein the shuttle is threaded during the loom operation, and is more particularly directed to means for imparting uniform tension to the thread during weaving and preventing wear of the metal parts by the constant attrition of the thread.

The present invention is a further development of the automatically threading shuttles shown and described in the patents to Edward S. Stimpson, No. 1,483,492, dated February 12, 1924, and No. 1,538,224, dated May 19, 1925, wherein the shuttle is provided with a thread casting device for casting the thread on the occurrence of a loop or overthrow as the shuttle is arrested in the shuttle box, and while the advantages of the present invention are well manifested in such character of shuttles, it may be employed advantageously with other kinds or characters of shuttles of the loom threading type. In shuttles of this type, the threading end portion of the shuttle is usually provided with a threading block having a longitudinally extending thread passage and at the forward end of the thread passage the thread is directed past the metal parts to the side delivery eye.

In weaving with certain characters or kinds of filling, such, for instance, as filling of fine count, silk, rayon, and the like, much difficulty has been experienced in providing a proper tension suitable to the slippery character of the yarn employed, and at the same time prevent attrition or wear of the metal parts over which the filling passes during weaving. Heretofore it has been proposed to provide shuttles with glass or porcelain thread guiding elements in an attempt to prevent wear or cutting of certain metal portions by the thread, but in such cases the glass or porcelain parts have not been disposed and arranged with due regard to the desired tension effect upon the thread in order to lay it properly in the shed, and in many cases the glass or porcelain parts have been so arranged as not to act effectively in the protection of the metal parts.

One of the important features of the present invention consists in providing a vitreous bridge at the forward end of the thread passage over which the thread passes, and in conjunction therewith a further vitreous member bridging the passageway leading to

the side delivery eye and under which the thread is deflected during weaving. Such vitreous elements have been found to protect the metal parts of the threading instrumentalities, and by combining such vitreous elements in their cooperative relation one with the other, the desired tension may also be imparted to the thread even though it be of fine count, silk, rayon, or the like.

In carrying out the invention, the vitreous bridge, formed either of glazed porcelain, glass or the like, is mounted in the shuttle at the forward end of the thread passage above the lower wall thereof and in the passageway leading to the side delivery eye a vitreous bridging member of like material is provided whose yarn-engaging surface is below the upper or yarn-engaging surface of the bridge, with the result that the yarn is deflected over the vitreous elements on its way to the side delivery eye, thereby not only protecting the metal parts but also furnishing the necessary continuous tension to the thread as it is withdrawn from the shuttle.

The invention and new features thereof and novel combination of parts will best be made clear from the following description and the accompanying drawings of one good practical form thereof.

In the drawings:

Fig. 1 is a plan view with some of the parts broken away, showing the threading end of a shuttle provided with the present invention;

Fig. 2 is an enlarged plan view of the threading block containing the present invention and detached from the shuttle;

Fig. 3 is an underside view of the threading block;

Fig. 4 is an end view of the threading block containing the present invention looking from the bobbin chamber;

Fig. 5 is a side elevation of the threading block; and

Fig. 6 is a perspective underside view of the threading block containing the present invention.

In the Stimpson Patent, No. 1,538,224, hereinbefore mentioned, the threading block is shown and described as formed of cast iron having a rust proof covering and provided in the longitudinally extending thread passage with a thread casting device or scroll for casting the thread out of the threading

block and thread passage on the occurrence of a loop or overthrow. The threading block of the present invention may be similarly formed or may be as described in the 5 Stimpson Patent, No. 1,483,492, and certain features of the present invention may be advantageously employed in various types of now well-known threading blocks or threading eyes.

10 The shuttle 1 is provided with the usual bobbin chamber 2 in which the filling carrier 3 may be detachably supported as is common in automatically threading shuttles, and forward of the bobbin chamber the shuttle is 15 provided with a threading block receiving chamber 4, while the front end portion of the shuttle may be provided with a recess 5 forming a leader for the thread during the first pick of the shuttle following replenishment.

20 Mounted in the threading block receiving chamber 4 is the threading block 6 which as hereinbefore stated may be substantially of the character shown and more fully described in the Stimpson patents. The threading block 6 is provided with a longitudinally extending thread passage 7 in which is located the thread casting device or scroll 8, the forward end portion 9 of which extends forwardly towards the end of the longitudinally 25 extending thread passage. As herein shown, the threading block 6 is provided with the side walls 10 and 11 and the bottom wall 12, between which the longitudinally extending thread passage is formed, and in the thread 30 passage adjacent the bobbin chamber is the thread casting device or scroll 8, the rear edge portion 14 of which extends upwardly, laterally and forwardly relative to the thread passage, with the result that on the 35 occurrence of a loop or overthrow the thread will be cast upwardly out of the thread passage to be subsequently rethreaded into the scroll or thread casting device on the following pick of the shuttle, as more fully 40 described in the Stimpson patent hereinbefore mentioned.

The scroll 8 may be secured in place by suitable means, and as herein shown its heel portion 14 extends through an opening in 50 the base of one of the side walls of the shuttle and is turned laterally at 15, in which respect it is substantially the same as shown and described in the Stimpson Patent, No. 1,538,224, and the threading block 55 may be secured in place in the shuttle by the usual cross-bolt, as described in the Stimpson patent last mentioned.

In accordance with the present invention, a bridge is provided at the forward end of 60 the thread passage and is independent of the threading block itself, and over the passage leading to the side delivery eye is a tensioning member for deflecting the thread from the bridge downwardly towards the 65 side delivery eye. In order that the metal

parts of the threading block may not be scored or unduly worn by the constant attrition of the thread during weaving, and also to provide proper tension to the thread as it is delivered from the shuttle, the bridge 70 and the tensioning member respectively are formed of vitreous material, such, for instance, as glass or glazed porcelain, with the result that the bridge and tensioning member not only protect the metal parts of 75 the threading block and shuttle from wear by the thread but also impart to the thread the desired uniform tension, a fact which is more particularly observable in weaving with thread of fine count, silk or rayon. 80

More particularly stated, the present invention provides a vitreous bridge 16 at the forward end of the thread passage 7 which is formed with a smooth and hardened thread engaging surface. As more particularly shown in Fig. 5, the vitreous bridge 16 has its upper thread engaging surface above the lower wall of the thread passage and preferably in the extended longitudinal axis of the thread casting device, while its forward surface, as at 17, extends forwardly beyond the lower wall of the thread passage. 90

Various means may be employed in securing the vitreous bridge 16 in the position described, but in the present instance of the invention the side wall 11 of the threading block is provided with a perforation 18, Fig. 1, of a size to admit the endwise passage of the vitreous bridge 16, and the opposite wall 10 of the threading block is provided with a recess 19, which does not extend through the wall, to receive and support the opposite end of the vitreous bridge when the latter has been passed through the opening 18 and extended into its bridge-forming position. When the threading block is secured in the threading block receiving chamber 4, the wood of the shuttle overlies the end 20 of the bridge and maintains the bridge in operative position. 100

The threading block of the present invention differs somewhat from the threading blocks shown and described in the Stimpson patents above mentioned, and in this respect the threading block is provided with a ledge or laterally extending wall 21 below the apron or thread director 22, as indicated in Figs. 4, 5 and 6, the forward edge portion of which constitutes the downwardly extending horn 23 which assists in directing the thread downwardly to the passage leading to the side delivery eye during shuttle threading, and the laterally extending wall 21 forms a support for the vitreous member 24. As indicated in Figs. 4 and 5, the wall 21 is provided with an opening 25 extending forwardly into the wall, of a size to accommodate the vitreous member 24, but the opening 25 does not extend to the front 110 115 120 125 130

wall or horn 23 but terminates short thereof, as indicated in Fig. 5, with the result that when the vitreous member 24 has been inserted endwise in the opening 25 and the threading block seated in the threading block receiving chamber formed in the shuttle, the wood of the shuttle or a shoulder 26 formed thereon overlies the rear end portion of the vitreous member 24 and maintains it in its operative position, as indicated in Fig. 1.

The vitreous member 24 may or preferably will be formed with a glazed and hardened thread engaging surface, as shown, and is mounted in the wall 21 above and over the passageway leading to the side delivery eye, with its lower thread engaging surface 27 below the thread engaging surface of the vitreous bridge 16, with the result that the thread passing over the bridge 16 will be supported above the lower wall of the thread passage and deflected downwardly from the overhanging front portion 17 of the bridge surface to and under the thread engaging surface 27 of the vitreous member 24. The vitreous surfaces of the bridge and member 24 will thereby impart to the deflected thread a tension appropriate to the character of the yarn in use and will at the same time protect the metal parts of the threading block from wear due to the attrition of the thread during weaving.

As hereinbefore stated, the vitreous member 24 is supported in the wall 21 extending downwardly from the upper portion of the threading block or apron 22, and in order to provide means for confining the thread in contacting relation with the vitreous member 24 as it passes on its way to the side delivery eye, the wall 21 is provided with a stop 28 adjacent the forward portion of the vitreous member 24 and a similar stop 29 adjacent the opposite portion of the vitreous member 24, the result being that as the thread is drawn longitudinally of and above the lower wall of the thread passage over the top of the vitreous bridge 16 and leads from the forwardly projecting or overhanging surface 17 of the bridge, it will pass downwardly under the thread engaging surface of the vitreous member 24 and be confined in position to engage such surface by the stops 28 and 29 as it passes to the side delivery eye.

As indicated in Fig. 1, the thread *a* passes from the filling carrier 3 into the longitudinally extending thread passage in a manner similar to the conditions that prevail in the Stimpson patent hereinbefore mentioned, and is guided through the scroll 8 over the upper surface of the vitreous bridge 16 in alignment with the axis of the scroll or above the lower wall of the thread passage and then downwardly over the forwardly projecting or overhanging surface 17 of the

vitreous bridge, and from here the thread passes downwardly without contacting with the metal parts of the threading block and engages the lower surface of the vitreous member 24 extending over or above the passageway leading to the side delivery eye, while the stops 28 and 29 confine the thread on its way to the side delivery eye into contacting relation with the vitreous member 24, the effect being that not only are the metal parts of the threading block protected from wear or scoring by the thread, but the surfaces of such vitreous elements impart to the thread, even though it be of slippery nature, the desired tension as it is delivered to the side delivery eye 30 of the shuttle during weaving.

From the construction described it will be apparent that the vitreous bridge 16 formed of glazed porcelain or glass or the like, extends transversely across the longitudinally extending thread passage to support the thread above the lower wall thereof, while the vitreous member 24, formed of similar material, extends transversely across the upper portion of the passage leading to the side delivery eye to deflect the thread downwardly from the bridge, the relation of the two vitreous elements being substantially, though not necessarily, at right angles to each other with their axes in different horizontal planes.

What is claimed is:

1. An automatically threading shuttle having a side delivery eye, a threading block having a longitudinally extending thread passage communicating with the side delivery eye, a horizontal vitreous bridge at the forward end and extending transversely of the thread passage over which the thread passes to the side delivery eye, and a horizontal vitreous thread engaging member arranged transversely over the passage leading to the side delivery eye at substantially right angles to the vitreous bridge and under which the thread passes on its way from the bridge to the side delivery eye to protect the shuttle parts from wear and provide uniform tension upon the thread as it is withdrawn from the shuttle during weaving.

2. An automatically threading loom shuttle having a side delivery eye and a longitudinally extending thread passage communicating with the side delivery eye, a vitreous bridge extending transversely of the longitudinally extending thread passage at the forward end thereof and above the lower wall of the thread passage over which the thread passes, and a substantially horizontal vitreous member above the passage leading to the side delivery eye and under which the thread is deflected as it is withdrawn from the shuttle during weaving.

3. An automatically threading loom shuttle having a side delivery eye, a threading

block having a longitudinally extending thread passage, a vitreous bridge at the forward end of the thread passage extending transversely thereof and over which the 5 thread passes, a vitreous member extending transversely above the passage leading to the side delivery eye, and having its thread engaging under surface below the top surface of the bridge to deflect the thread downwardly from the bridge as it is withdrawn 10 from the shuttle during weaving.

4. An automatically threading loom shuttle having a side delivery eye, a threading block having a longitudinally extending 15 thread passage terminating at its forward end in a vitreous bridge the top of which is above the lower wall of the thread passage and over which the thread passes on its way to the side delivery eye, a vitreous member 20 supported by the threading block over the passage leading to the side delivery eye and having its under surface below the top surface of the bridge that the thread may be deflected downwardly from the bridge on 25 its way to the side delivery eye to tension the thread and prevent wear upon the metal of the threading block during weaving.

5. An automatically threading loom shuttle having a side delivery eye, a threading block having a longitudinally extending 30 thread passage, a horizontal vitreous bridge at the forward end of the thread passage having its thread engaging surface above and forward of the lower wall of the 35 thread passage, a vitreous member arranged transversely over the passage leading to the side delivery eye and having its under thread engaging surface below the thread engaging surface of the vitreous bridge to deflect the 40 thread downwardly and tension the thread on its way to the side delivery eye.

6. An automatically threading loom shuttle having a side delivery eye, a threading block having a longitudinally extending 45 thread passage, a vitreous bridge at the forward end of the thread passage having its

thread engaging surfaces above and forward of the lower wall of the thread passage, a vitreous member arranged transversely over the passage leading to the side delivery eye and having its under thread engaging surface below the thread engaging surfaces of the vitreous bridge to deflect the thread downwardly and tension the thread, and means for confining the thread on the vitreous member as it travels to the side delivery 55 eye.

7. An automatically threading loom shuttle having a side delivery eye, a threading block having a longitudinally extending 60 thread passage, a vitreous bridge at the forward end of the thread passage extending transversely thereof and over which the thread passes, a vitreous member extending transversely above the path of the thread 65 on its way to the side delivery eye and having its thread engaging surface below the top surface of the bridge to deflect and tension the thread during weaving, and means for supporting the vitreous bridge and vitreous member in their transverse relations to the respective thread passages.

8. An automatically threading loom shuttle having a side delivery eye, a threading block having a longitudinally extending 70 thread passage communicating with the passage leading to the side delivery eye, a vitreous bridge having a hard thread engaging surface extending transversely of the thread passage at the forward end thereof and projecting forward of the lower wall of the thread passage, a vitreous bridging member extending transversely above the passage-way leading to the side delivery eye and having its thread engaging surface below the 75 thread engaging surfaces of the bridge to protect the threading block from wear and deflect and tension the thread as it is withdrawn from the shuttle during weaving.

In testimony whereof, I have signed my 80 name to this specification.

WALLACE I. STIMPSON.
